UNITED STATES PATENT OFFICE.

HENRY HELLWEG, OF MILWAUKEE, WISCONSIN, ASSIGNOR OF ONE-HALF TO LOUIS SCHLESINGER, OF MILWAUKEE, WISCONSIN.

PACKAGE-HOLDER.

1,285,162.

Specification of Letters Patent. Patented Nov. 19, 1918.

Application filed November 2, 1916. Serial No. 129,112.

To all whom it may concern:

Be it known that I, HENRY HELLWEG, a citizen of the United States, residing at Milwaukee, in the county of Milwaukee and State of Wisconsin, have invented certain new and useful Improvements in Package-Holders, of which the following is a specification, reference being had to the accompanying drawing, forming a part thereof.

This invention relates to package holders and the object of the invention is to improve package holders in the manner to be hereinafter described and claimed.

Referring to the drawings which accompany this specification and form a part hereof, which drawings illustrate an embodiment of this invention, and on which drawings the same reference characters are used to designate the same parts wherever they may appear in each of the several views, Figure 1 is an elevation, partly in section, of a package holder in use; Fig. 2 is a section taken on the line 2-2 on Fig. 1, looking in the direction indicated by the arrows; Fig. 3 is a top, plan view of the package holder; and Fig. 4 is a bottom, plan view of the package holder, a part being shown in section.

Referring to the drawings, the package holder is composed of a base 1 which is so constructed as to slidably receive or hold a fastening member 2. It is preferred to form the base 1 as a channel member provided with flanges 3 and 4 and the fastening member 2 can lie in the channel 5. Separated bearings 6 and 7 are adapted to rest against the running board of an automobile or any other suitable support 8 and any suitable clamping device, such, for example, as the screw 9, carried by a bracket 10, engages with the support 8 between the bearings 6 and 7 to firmly secure the package holder to the support. It is preferred to have the flanges 3 and 4 elevated above the support 8, as clearly shown by Fig. 1 of the drawings, so that dirt, water or snow will not be collected if the package holder is used in an exposed situation as on the running board of an automobile. It is also preferred to provide the package holder with adjustment means so that the fastening member 2 can

be engaged with the package holder to a greater or less extent to correspond with the size of a package to be held. This object can be accomplished by providing a plurality of members such, for example, as the parts 11, 12, 13, 14, 15, 16, 17 and 18 of the base 1 with one or more of which the fastening member 2 can be engaged in a manner which will be readily understood. Two or more of the package holders can be used for a long package as clearly shown by Fig. 2 of the drawings, and the fastening member 2 can be any suitable flexible device such as an ordinary strap.

The members or parts 11, 12, 13, 14, 15, 16, 17 and 18 of the base 1 provide apertures 19, 20, 21, 22, 23, 24 and 25 through which the fastening member 2 can be passed and apertures 26 and 27 are preferably provided so that the fastening member 2 can be passed lengthwise entirely through the base 1.

What is claimed is:

1. A package holder comprising a base having an aperture in one end adapted to receive a fastening member, the top of the base being provided with a plurality of apertures through either one of which the fastening member is adapted to be passed, the base being provided with flanges and bearings, the bearings being adapted to rest against a support, the lower edges of the flanges being elevated above the support, and means adapted to clamp the base to the support at a point between the bearings.

2. A package holder comprising a base having apertures at separated points in its length to receive a flexible fastening member for securing packages, depending bearings on the under side of said base, said fastening member being freely adjustable lengthwise of said base when it is secured in place to a support, and a clamping device arranged to engage the support on the opposite side from and between said bearings.

3. A package holder comprising a base having apertures at separated points in its length, stiffening flanges along the longitudinal edges, and separated depending bearings, a fastening member passing through said apertures and freely adjustable lengthwise of said base when it is secured in place

to a support, and a clamping device arranged to engage the support on the opposite side from and between said bearings.

4. A package holder composed of a base 5 provided with depending flanges, bearing members, a bracket and a clamping device, the base being provided with a plurality of apertures through which a flexible fastening

member may be passed to secure a package to the base with the base interposed between the fastening member and the package so that the fastening member is free to be moved back and forth.

In witness whereof I hereto affix my signature.

HENRY HELLWEG.
